Primary Examiner — Michael A. Pratt*Assistant Examiner* — Wendy Arminio(74) *Attorney, Agent, or Firm* — Berkeley Law & Technology Group LLP(57) **CLAIM**

The ornamental design for a cap with bottle opener, as shown and described.

DESCRIPTION

FIG. 1 is a top and front perspective view of a cap with bottle opener showing our new design;

FIG. 2 is a front elevational view of FIG. 1;

FIG. 3 is a back elevational view of FIG. 1;

FIG. 4 is a right side elevational view of FIG. 1;

FIG. 5 is a left side elevational view of FIG. 1;

FIG. 6 is a top plan view of FIG. 1;

FIG. 7 is a bottom plan view of FIG. 1; and,

FIG. 8 is an isometric view of the cap with bottle opener showing the cap with bottle opener in use on an unclaimed cup.

The broken lines in FIG. 8 represent environmental subject matter and form no part of the claimed design. All other broken lines depict portions of the cap with bottle opener that form no part of the claimed design.

1 Claim, 5 Drawing Sheets(56)
